UNITED STATES PATENT OFFICE

115,265

DESIGN FOR A BADGE OR SIMILAR ARTICLE

William M. Itton, Chicago, Ill.

Application March 11, 1939, Serial No. 83,517

Term of patent 7 years

To all whom it may concern:

Be it known that I, William M. Itton, a citizen of the United States, residing at Chicago, in the county of Cook and State of Illinois, have invented a new, original, and ornamental Design for a Badge or Similar Article, of which the following is a specification, reference being had to the accompanying drawing, forming part thereof.

Fig. 1 is an enlarged perspective view of a badge or similar article showing my new design.

Fig. 2 is a front plan view thereof.

Fig. 3 is a side elevational view looking in the directions of the arrows 3—3.

Fig. 4 is a cross sectional view taken on lines 4—4 of Fig. 2.

I claim:

The ornamental design for a badge or similar article, as shown.

WILLIAM M. ITTON,
